US00D896396S

(12) **United States Design Patent** (10) **Patent No.:** **US D896,396 S**
Wersland et al. (45) **Date of Patent:** **** Sep. 15, 2020**

- (54) **PERCUSSIVE MASSAGE DEVICE**
(71) Applicant: **Theragun, Inc.**, Beverly Hills, CA (US)
(72) Inventors: **Jason Wersland**, Manhattan Beach, CA (US); **Benjamin Nazarian**, Beverly Hills, CA (US); **Jaime Sanchez Solana**, Los Angeles, CA (US); **Trent Hernandez**, Los Angeles, CA (US); **Rene Oehlerking**, Los Angeles, CA (US); **Dennis Matthew Puhalla**, Chicago, IL (US); **Jillian Tackaberry**, Chicago, IL (US); **Gary Paulsen**, Chicago, IL (US)
(73) Assignee: **THERAGUN, INC.**, Beverly Hills, CA (US)
(**) Term: **15 Years**
(21) Appl. No.: **29/719,078**
(22) Filed: **Dec. 31, 2019**

CLAIM

The ornamental design for a percussive massage device, as shown and described.

DESCRIPTION

FIG. 1 is a top perspective view of a percussive massage device, showing our new design;
FIG. 2 is a right side elevational view;
FIG. 3 is a left side elevational view;
FIG. 4 is a front elevational view;
FIG. 5 is a rear elevational view;
FIG. 6 is a top plan view of;
FIG. 7 is a bottom plan view; and,
FIG. 8 is a bottom perspective view.
